CLAIM

The ornamental design for a dispensing top for liquids, such as olive oil as shown and described.

DESCRIPTION

FIG. 1 is an oblique perspective view of the dispensing top for liquids, such as olive oil;

FIG. 2 is a front view of the dispensing top for liquids, as shown in FIG. 1;

FIG. 3 is a back side view of the dispensing top for liquids;

FIG. 4 is a right side view of the dispensing top for liquids;

FIG. 5 is a left side view of the dispensing top for liquids;

FIG. 6 is a top view of the dispensing top for liquids; and,

FIG. 7 is a bottom view of the dispensing top for liquids.
